WIREWORKING MACHINE

Ezra A. Frantz, Weatherford, Tex.

Substituted for (abandoned) application Serial No. 718,422, March 31, 1934. This application November 1, 1935, Serial No. 47,843

10 Claims. (Cl. 140—73)

My invention relates to wire working machines and more particularly to a machine for forming bale tie buckles from wire; and the object is to provide machines for this purpose with the minimum number of parts and which is inexpensive to make and run.

Another object is to provide a wire working machine with a common shaft adapted to continuously rotate with a plurality of wheels and cams 10 that direct and form the bends of the buckle and then sever the same from the wire stock.

Still another object of this invention is to provide a wire working machine having a combined die, holder, and cutter for the wire.

15 An advantage of this invention is that the simplicity of the mechanism permits the operation of a battery of machines with only the attention of one operator.

Another advantage of this invention is that the 20 adaptation of the machine to operate continuously eliminates considerable wear usually found in machines where the parts are driven intermittently.

Other objects and advantages will be fully explained in the description and the invention will 25 be more particularly pointed out in the claims.

Reference is had to the accompanying drawings which form a part of this application:

Fig. 1 is a side elevation of the machine.

30 Fig. 2 is a plan view of the same, shown with a portion of the top removed to more clearly illustrate the parts thereof.

Fig. 3 is a diagrammatic perspective view of a portion of the machine, showing the elements 35 used in bending the wire.

Fig. 4 is a diagrammatic illustration showing the various portions of the rotation of the common shaft used in bending the wire in its various angles to form the buckle.

40 Fig. 5 is a plan view of a die used in the machine for forming the rectangular portion of the buckle.

Fig. 6 is a side elevation of the buckle.

45 Fig. 7 is a detail view of the portion of the machine used in guiding, directing, and forcing the wire to the point of forming the same.

Fig. 8 is a detail of that portion of the machine used in holding the wire so that the same may be 50 bent to form the buckle. This view also illustrates the combined die, holder, and knife for severing the buckle from the wire stock.

Fig. 9 is a detail view of the portion of the machine used in bending the wire around the die 55 shown in Fig. 5.

Fig. 10 is a detail view of the portion of the ma-

chine used in bending the wire around the combination die shown in Fig. 8.

Fig. 11 is an end view of the machine.

Fig. 12 is a detail view of a portion of the machine showing a variation in the structure of the 5 same for forming the wire into a square form in cross section, as it is being fed into the bending portion of the machine.

Fig. 13 is a plan view of the mechanism used in forming the wire around the die shown in Fig. 5. 10

Fig. 14 is an inverted plan view of the combination die, showing the method of bending the wire in the formation of the buckle.

Fig. 15 is an inverted plan view of the combination die, holder, and cutter. 15

Figs. 16, 17, and 18 are side elevations of the lower portion or holding, forming, and cutting portions of the combination unit shown in Fig. 15.

Similar characters of reference are used to indicate the same parts throughout the several 20 views.

The machine consists of a base frame 1 having a drive shaft 2 journaled therein. The shaft 2 is provided with a drive pulley 3 or other suitable medium for motive power. The shaft 2 is 25 provided with a cogwheel 4 keyed thereto and adapted to mesh with and drive a gear wheel 5. The wheel 5 is keyed to a shaft 6 which is journaled in the frame 1.

The shaft 6 is provided with a plurality of cams 30 keyed thereto which function to operate the various contacting members with the wire for forming and severing the same from the wire stock. The shaft 6 is also provided with a feed wheel 7 which is made rigid with the same and adapted 35 to force the wire into the machine.

The feed wheel 7 is provided with a groove 8, in its outer periphery, in which the wire is directed to travel, as shown in Figs. 7, 11, and 12. An idler feed wheel 9 is resiliently rotatably journaled in the frame 1 of the machine and adapted 40 to engage feed wheel 7. This wheel 9 is also provided with a similar groove in its outer periphery which is adapted to cooperate with the wheel 7 to force the wire into the machine. A portion of the groove 8 of the wheel 7 is made of less depth 45 than the rest of the groove, and this portion 10 engages the wire and grips the same between the two wheels 7 and 9 and forces the wire to move in the direction of the travel of the wheel 7.

The object of forming the groove 8 in various depths permits the wheel 7 to rotate a portion of its turn without causing a movement of the wire, thus permitting continuous rotation of the wheel 50 with only an intermittent movement of the wire; 55

or, as the wheel rotates the wire will be intermittently fed to the machine. Each of the wheels 7 and 9 is provided with an integral face gear wheel which are intermeshed to insure perfect cooperation of the feed portions of the wheel.

The idler wheel 9 is rotatably mounted in an arm 11 which is resiliently mounted in the frame 1. The arm 11 serves as the bearing for the wheel 9 and its face gear 12. One end of the arm 11 is pivotally attached to an extension bracket 13 of the machine, and the other end of the arm is connected to the machine frame by means of a coil spring 14. The spring 14 is adapted to bear against the arm 11 in such a manner as to exert pressure of the wheel 9 against the wire which passes between the two wheels 7 and 9.

A portion of the frame 1 of the machine is formed to serve as a track for the wire as it is forced into the machine. This portion 15 of the machine is made rigid with the base or frame 1 of the machine and is also formed to serve as a bearing surface for the various members of the machine. A stop for the wire is adjustably mounted on a bracket 16 which is secured to the frame of the machine and which is provided with an adjustable block 17 bolted thereto. The block 17 is adapted to be moved to or from the wire 18 to vary the distance that the wire may be forced into the machine.

When the wire is fed into the machine, by means of the wheels 7 and 9, it will contact with the stop block 17 simultaneously with the time in which the groove 8 of the wheel 7 passes beyond such a position as to bind the wire 18 between the two feed wheels 7 and 9. Upon contact of the wire 18 with the stop, a retaining member 20 is forced down on the wire and adapted to hold the same in a secure manner so that it may be bent into the desired shape to form a buckle. The member 20 consists of a bar which is journaled in the machine and adapted to be actuated therein to serve a three-fold purpose, namely hold the wire when the same has been fed into the machine until its end rests against the stop, serve as a die for forming the wire, and serve as a knife for severing the completed form from the wire stock. Each end of the bar is provided with the necessary edge and contour for serving these purposes so that it may be reversed when either end becomes worn.

The bar 20 is pivotally connected to the lever 21 by means of a head 22. The head 22 is rigidly attached to one end of the bar 20, so that it may serve to gage the depth to which the bar 20 may be reciprocated into the machine and in engagement with the wire. The head 22 consists of a cylindrical shaped form, one end of which is drilled to receive the end of the bar 20, and the other end is drilled and tapped to receive a set screw 23. The set screw is threaded into the head 22 until it bears against the end of the bar 20. A second set screw 24 is provided in the head 22 and this set screw threads into the side of the head 22 and against the side of the bar 20 for insuring a stable connection of the head 22 with the bar 20.

One end of the lever or bar 21 is pivotally connected to the head 22 so that it may actuate the same for reciprocating the bar 20. The end of the lever 21, opposite its connection with the head 22, is provided with a projection 25 which extends into a face cam 26. The cam 26 is keyed to the shaft 6 and driven thereby. The cam 26 serves to actuate the bar 20 so that it will first hold the wire 18 and then sever the bent portion

of the wire from the stock. A tip 27 is provided on the end of the bar 20 which serves as a die in forming the hook portion of the bend in forming the wire buckle. The lever 21 is pivotally connected to the member 15 of the machine.

After the bar 20 is actuated so that it engages and holds the wire 18 against the stop block 17, a swinging arm 28 engages the wire intermediate the stop and bar 20 and bends the wire around a stationary forming block 29. This is the first bend in forming the buckle. The arm 28 is preferably made in the form of a hook having an axle 30 made rigid therewith and projecting at right angles from the arc thereof. A pinion 31 is made rigid with the axle 30 and this whole assembly is journaled in the machine so that it may be actuated by one of the cams which are keyed to the axle 6. A rack 32 is slidably mounted in the body of the machine so that it may be actuated by one of the cams and drive the pinion 31 so as to swing the arm 28 for forming the first bend of the wire. The axle 30 and its pinion 31 are positioned at a slight angle to the longitudinal center of the wire 18 so that the swing of the arm 28 will direct the end of the wire 18 to bend around the forming block 29 and place the end of the wire to one side of the body of the wire, as shown in Fig. 5, thus forming an approximate rectangular form of a bend. One end of the rack 32 is pivotally connected to a lever 33. The other end of the lever 33 is pivotally anchored to the frame of the machine, and intermediate its end, is a projection 34 which extends into and is adapted to ride in the face groove of a cam wheel 35. The cam wheel 35 is keyed to the shaft 6 of the machine and is adapted to be driven thereby. When the cam 35 actuates the lever 33 and its rack 32, the arm 28 will be moved to bend the wire 18 into an approximate rectangular form.

When the oscillating arm 28 as shown in Fig. 3, has been actuated, to bend the wire, the wire is then bent at right angles to the first bend by means of an arm 36. The arm 36 is rotatably mounted in the body 15 of the machine and positioned around the reciprocating arm 20. The arm 36 is provided with a cylindrical shaft made rigid therewith and adapted to fit around the rod 20. A pinion 37 is keyed to the hollow cylindrical shaft 38 and adapted to mesh with and be driven by means of a rack bar 39. One end of the bar or rack 39 is pivotally connected to a lever 40. The end of the lever 40, opposite its connection with the rack 39, is provided with a projection 41 which extends into and rides a face groove of the cam 42. The cam 42 is keyed to the shaft 6 and driven thereby for actuating the rack 38 and its cooperating parts. The lever 40 is preferably formed to serve as a crank arm with its bend pivotally connected to a portion of the body of the machine. When the cam wheel 42, and its cooperating parts, actuate the arm 36 to bend the wire 18 the wire is bent to form a hook-like part 18' or form the severed end. When the arm 36 is oscillated to form the hook portion 18' of the buckle, the first bend or the rectangular form of the wire 18 is moved off of the stationary block 29. The rectangular form of the wire 18 was first formed on the block 29 adjacent the end of the block by an arm 28 having an axis 36 positioned at right angles to the axis of the arm 28. This arrangement permits the arm 36 to remove the rectangular form of the buckle from its forming block 29 as it forms the hook 18'. After this hook-like bend 18' is made in the wire the 75

buckle is completed and the bar 20 is further moved, as explained above, to sever the buckle from the wire stock thus completing the forming operation of the machine.

5 The structure of the machine permits a continuous rotation of the cams and gears during the forming and severing of the buckle. The wire 18 may be fed to the machine through a forming mechanism for pressing and forming the 10 same into an approximate square in cross section. This mechanism consists of a pair of feed wheels 7 and 9, similar to those described above, but provided with V shaped grooves in their outer peripheries, as shown in Fig. 12.

15 Fig. 14 illustrates a method of using the tip of the bar 20 for a forming member for the bend 18' of the wire 18, as well as the use of a tube conduit 44 for the wire 18 cooperating with the severing edge of the bar 20 for cutting the buckle 20 from the wire stock. The end of the tube 44 is cut off at an angle to its longitudinal center and provided with a notch or cavity 45 for receiving the end of the wire 18, as it is bent to its place adjacent to and at right angle to the wire, 25 as it passes through the conduit 44. The notch 45 serves to hold the end of the wire 18 in place as the bar 20 is actuated to sever the completed buckle from the wire stock. When the bar 20 is moved to sever the wire, the flat side 30 of bar 50 adjacent the end of the tube conduit 44, will cooperate with the flat end surface of the tube to act as a knife for cutting the wire 18.

In the spring tension of the member 11, a vertical bar 46 is made rigid with the frame of the 35 machine and adapted to extend through the spring end of the member 11. A stop 47 is positioned on the bar 46, beneath the bar 11 and adjustably positioned thereon so as to limit the downward movement of the member 11 and its 40 wheels 9 and 7, to the extent that the same will not bind the wheel 7, when the wheel 7 is permitted to rotate without moving the wire 18. The spring 14 is positioned around the bar 46 and is interposed between the member 11 and the 45 adjusting nut 48 of the rod or bar 46 so that the tension on the member 11 may be varied.

The actuating cams 26, 35, and 42, and the 50 feed wheel 7, all being keyed to the same shaft 6 necessitates the forming of each of their actuating surfaces so that they will be distributed around their axis in a cooperating manner, as 55 illustrated in Fig. 4. This arrangement permits the continuous-intermittent action of all forming, holding, and severing actions of the machine without an intermittent action of the main actuating shaft 6. The continuous action of the machine driven shaft 6 cooperates and drives mechanism to move the wire 18 to the 60 stop 17, move the bar 20 to hold the wire 18, oscillate the arm 28 to form the first bend or 65 form the rectangular form of the buckle, bend the rectangular form to form the hook 18', and again move the bar 20 to sever the completed buckle from the wire stock. The sectors of the shaft used in performing these functions, in the order named, may be diagrammatically illustrated as shown in Fig. 4.

The body of the machine or the block 1 is 70 provided with a grooved plate or conduit 44 for receiving the wire 18 and directing it to the point where it is bent to form the buckle, shown in Fig. 6. The end of the conduit 44, adjacent the combination unit 20, is formed to serve as a cutting edge that cooperates with a cutting portion

of the member 20 for severing the completed wire buckle from the wire stock.

In Figs. 15 to 18 inclusive, the various portions of the member 20 are illustrated to show parts used for holding, forming, and severing the wire 18. The body of the member 20 is preferably round in cross-section. The lower end of the member 20 is cut-away to form a surface 50 which is adapted to be moved adjacent the cutting end of the plate or conduit 44. The extreme lower end 27 of the member 20 serves to contact with and hold the wire 18 while the wire is being bent to form the buckle. This portion 51 also serves as a die to form the wire 18 as it is being bent, by the member 36. A portion 52 of the bar 20 is formed into a cutting edge to cooperate with the cutting end of the conduit 44 in severing the completed wire buckle from the wire stock.

In Fig. 14 the rectangular forming die and 20 the member 20 of the machine is shown in an inverted position. The wire is shown in dotted outline indicating its bend around the rectangular forming die 29. From the die 29, the wire 18 is bent around the portion 27 of the member 20 25 by the member 36, as shown in full lines, Fig. 14. After the wire 18 is bent, as shown in full line, the member 20 is actuated to sever the completed wire buckle from the wire stock as previously described. 30

This application is filed as a substitute for application Serial No. 718,422, filed March 31, 1934, and subsequently abandoned.

What I claim is:

1. A wire working machine including a wire 35 feeder, a forming block and a die, said feeder being adapted to feed wire over said forming block of said machine, means for bending said wire around said block to form an approximate rectangular form, means for bending said rec- 40 tangular form around said die and off of the end of said block for forming a loop in said wire adjacent to and at right angles to said form, and a means for actuating said die for severing said bent wire from the stock thereof. 45

2. A wire working machine for forming cotton bale tie buckles and the like including a wire 50 feeder, a stop and a pair of dies, said feeder being adapted to direct wire into said machine and against said stop which is adjustably disposed therein, a plurality of arms disposed in said machine and adapted to be actuated for bending the ends of said wire around one of said dies for forming an approximate rectangular form, said arms being adapted to bend said rec- 55 tangular form around a second die, and means for actuating said second die for severing said form from the stock of wire.

3. A wire working machine including a wire 60 feeder, a stop, a stationary form and a movable die, said feeder being adapted to direct wire into said machine and against said stop, said die being disposed in said machine and adapted to hold said wire therein while the same is being formed, means for bending the end of said wire 65 around said form, means for bending said wire off of said form at right angles to said first bend and around said die, and means for actuating said holding die for severing said bent form from the stock of wire. 70

4. A wire working machine including an adjustable stop adapted to receive the end of a wire directed therein, a die disposed in said machine and adapted to hold said wire against said stop, means interposed between said die 75

and said stop for forming said wire into an approximate rectangular form, means for moving said rectangular form for forming a loop in said wire at right angles to the longitudinal sides of said rectangular form, means for severing said formed wire from the stock thereof, a plurality of continuously rotating cams operatively disposed in said machine for actuating said directing, holding, forming and severing means.

5. A wire working machine including a feeder and a stop operatively carried in said machine, said feeder being adapted to abut the end of said wire against said stop, means for holding 10 said wire against said stop, means intermediate said stop and said holding means for bending said wire into an approximate rectangular form, means for bending said rectangular form to form a hook around the end of said wire and 15 at right angles to the longitudinal sides of said rectangular form, and said holding means being adapted to sever said bent form of wire from the stock of wire fed to said machine.

6. A wire working machine including a feeder 25 and a stop operatively carried in said machine, said feeder being adapted to abut the end of said wire against said stop, means for holding said wire against said stop, means interposed between said stop and said holding means for bending 30 said wire into an approximate rectangular form, means for bending said rectangular form around said holding means for forming a hook around the end of said wire, and said holding means being adapted to sever the bent form of 35 said wire from the stock of wire fed to said machine.

7. A wire working machine having a stop, a wire feeder and an adjustable die, said feeder being adapted to direct wire into said machine and against said stop, a die carried in said machine and adapted to hold said wire within said

5. machine, a forming block rigidly disposed in said machine, means for bending the end of said wire around said forming block, means for bending said wire around said first-named die, and means for actuating said first-named die for severing said bent form of wire from the stock thereof.

8. A wire working machine for forming cotton bale tie buckles and the like, including a wire feeder and a stop, said feeder being adapted to 10 direct wire into said machine so that the end of the same will be brought to and against said stop which is adjustably carried in said machine, means for holding said wire against said stop, a block carried in said machine, means interposed between said stop and said holding means for bending said wire around said block, means for bending said wire around said holding means and at right angles to said first-named bend, and means for severing said bent portion 15 of said wire from the stock thereof.

9. A wire working machine including a feeder adapted to direct wire to a plurality of bending arms operatively disposed therein, means cooperating with one of said arms for severing the bent 25 wire from the stock thereof, a plurality of cams rotatably mounted in said machine and provided with a common drive shaft, said cam being adapted to actuate said feeder, severing means and bending arms, and means for actuating said 30 shaft.

10. A wire working machine including an adjustable stop for receiving the end of a wire direct into the machine, means adjacent said stop for bending said wire into an approximate 35 rectangular form, means for bending said rectangular form of wire so as to form a loop in the end of said wire and at right angles to said rectangular form, and means for severing said bent form of wire from the stock thereof.

EZRA A. FRANTZ.
